UNITED STATES PATENT OFFICE.

CONRAD GEBHARD, OF MUNICH, GERMANY, ASSIGNOR TO "ASFAG" AKTIEN-GESELLSCHAFT, OF GLARUS, SWITZERLAND.

AUTOMATIC LOCKING DEVICE.

1,378,447.

Specification of Letters Patent. Patented May 17, 1921.

Application filed August 12, 1920. Serial No. 403,163.

To all whom it may concern:

Be it known that I, CONRAD GEBHARD, a citizen of the Republic of Germany, residing at Munich, Tegernseerlandstrasse 135, Germany, have invented certain new and useful Improvements in Automatic Locking Devices; and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

Several constructions of automatic locks which are actuated by the closing of the door are already known particularly in rail-way-cars and other vehicles.

Locks of this type are provided with a bolt influenced by the closing spring, which bolt is secured in the open- and closed-position by a locking lever which can be released either by hand or by closing the door.

The present invention relates to that type of locks but it differs essentially from the known locks by its simpler construction, cheaper cost of manufacture and by its more reliable manner of working.

An essential feature of the invention consists in the provision of a releasing member which can be raised by means of a tappet or latch to actuate the locking lever securing the bolt. The end of the locking lever projects beyond the end face of the lock casing, in a known manner, into the path of a vertically displaceable gliding member in the keeper. This gliding member has an inclined face that yieldingly engages the end of the locking lever when the door is being opened but when the door is being closed the gliding member is in fixed position and causes a displacement of the locking lever and a release of the bolt. The different parts are in such an operative engagement with each other that the lever locking the bolt may be lifted by operating the tappet by hand when the door is being opened or automatically by means of the guide piece when the door is being shut.

A preferred form of the invention is shown on the accompanying drawing, on which:

Figure 1 shows a lock in front elevation, the cover plate being removed;

Fig. 2 is an end view of the keeper;

Fig. 3 is a section along line A—B of Fig. 1;

Fig. 4 shows the lock in the bolted position;

Fig. 5 is a side view of the lock.

The bolt *a* of the lock fitted to a door is in its front part *b* preferably square, its front edges may be beveled as is customary but is not necessary. Above the bolt *a* which is influenced by a spring *c*, a locking lever *e* is mounted on pivot *d*, and rests against the base plate *f* of the lock. Said lever is fitted with a lug *g*, which according to the position of the bolt is pressed into notches *i*, *k* of the bolt *a* by the action of a spring *h* on said locking lever. The upper edge of the bolt between the notches *i* and *k* is beveled. A releasing member *l*, *m* abuts against the lug *g* of the locking lever, the vertical shank *l* being guided in guide plates *n* and *o* fitted to the base plate *f* of the lock. Below the locking end *b* of the bolt *a* a lug *p*, which may be actuated by hand for instance by means of a latch, is turnably mounted, and can be brought into engagement with a projecting part *q* of the bolt *a*, *b*, through which engagement the bolt *a*, *b* is moved in the direction of the arrow and the lock unbolted. The lug *p* is influenced by a spring *r* and is provided with a projecting part *s* which rests in a lateral direction on the base plate of the lock and in a radial direction against the horizontal shank *m* of the releasing member.

The locking lever *e* projecting through the end plate *t* of the lock is, as is shown in Fig. 5, beveled across two opposite edges of its square section, so that its outer end forms a continuation *u* which is arranged obliquely to the vertical. The keeper *v* fitted to the door frame is provided on its inner side with a vertically movable gliding member *w* guided in a slot *l* of the keeper and projects outside the latter forming a stop *x* which is arranged at an angle to the vertical. The stem *y* of the gliding member *w* is influenced by a spring *z* which normally holds the stop *x* in the path of the part *u*.

The manner of operation of the lock is as follows: In the position shown in Fig. 1 the front part *b* of the bolt is free of the keeper *v* so that the door may be opened by turning it out. The gliding member *w* which is situated behind the end *u* of the locking lever *e* (as is shown in Fig. 2 in chain-dotted lines) 110

is moved toward the oblique gliding member α , abuts against the latter from the rear. This movement lifts the gliding member α , α which is adapted to be displaced in this direction, in consequence of the oblique arrangement of said engaging parts into the position shown in chain-dotted lines in Fig. 2, in which position the part u of the locking lever e is permitted to pass below the gliding member α and the door can be opened, whereupon the gliding member is brought back into its normal position by the action of the spring.

Assuming now the open door to be closed, the part u is brought into engagement with the member α from the opposite side. The latter part rests on the lower end of slot 1 and cannot yield, therefore the oblique part u of the locking lever glides along the oblique face of member α whereby the locking lever e is lifted against the action of the spring h until it is free of member α . As soon as this occurs, the locking lever e is lifted to such an extent, that its lug g disengages the notch k (this position of the locking lever is shown in chain-dotted lines in Fig. 1), whereupon the bolt a is driven into engagement with the keeper by the action of spring c and the lock and the door is bolted, which position is shown in Fig. 4.

The locking lever e is then pressed downward by means of the spring h and the lug g comes into engagement with the notch i , whereby the bolt is secured against carrying out an undesired unlocking movement. The spring r at the same time turns the tappet p into its proper engaging position. In order to unbolt the lock and open the door the tappet p is turned in the direction of the arrow indicated in Fig. 4 that is in an anticlockwise direction, by means of a handle or a trigger located on the inside or outside of the door. In consequence of this turning motion the projecting part s of the tappet p which rests against the shank m of the releasing member lifts the latter. The vertical shank l presses the lug g of the locking lever which is in the notch i in an upward direction until the notch is disengaged. Upon a further turning of the tappet p the latter comes into engagement with the edge q of the bolt, whereby the bolt is pushed back in the direction of the arrow shown in Fig. 4 and is thus drawn out of the keeper, the lug g glides along the oblique face 2 which connects the two notches i, k . As soon as the bolt is pushed back far enough for the lug g to leave the oblique surface 2, the lug snaps into the notch k , the tightened spring r turns the tappet p back and all the parts are again in their relative positions illustrated in Fig. 1.

The locking lever which can be brought out of engagement by closing the door as well as by hand by actuating the tappet secures the bolted lock reliably against any undesirable opening caused by the vibration of the vehicle, as the bolt which is inserted deeply into the keeper cannot leave the latter for these reasons. The locking lever may be so adjusted that only a slight pressure *i. e.* a very gentle closing of the door causes its disengagement. The lock is of a flat shape so that it does not take up much room nor requires large recesses on the door.

I claim:

1. An automatic locking device, comprising a spring actuated bolt having notches formed therein, a keeper, a spring actuated locking lever adapted to engage said notches the end of said lever projecting beyond the end cover of the lock in the direction of the keeper, a spring urged tappet pivotally mounted on the base plate of the lock and adapted to be turned to cause a withdrawal of the bolt from the keeper, a releasing member interposed between the tappet and the lever for releasing the latter upon a turning of the tappet, and a member arranged in the keeper adapted to be brought into yielding engagement with said projecting end of the lever when the door is being opened and acting as a fixed guiding face which engages the end of the locking lever and releases the bolt when the door is being shut.

2. An automatic locking device, comprising a spring actuated bolt having notches formed therein, a keeper, a spring actuated locking lever adapted to engage said notches, the end of said lever projecting beyond the lock casing in the direction of the keeper, and provided with a face arranged obliquely to the vertical direction, a spring urged tappet pivoted on the base plate of the lock and adapted to be turned to cause a withdrawal of the bolt from the keeper, a lug rigidly fixed to the tappet, a releasing member having a vertical shank abutting against said locking lever and a horizontal shank resting on said lug fitted to the tappet whereby the locking lever is lifted out of engagement with the bolt upon a turning of the tappet, and a vertically displaceable member having an inclined face in the path of the oblique end of the locking lever and displaced by the latter in a vertical direction when the door is being opened and acting as a fixed guide face over which the face of the locking lever glides, whereby the latter is lifted and the bolt released when the door is being shut.

In testimony that I claim the foregoing as my invention, I have signed my name.

CONRAD GEBHARD.
